[57] CLAIM

The ornamental design for a grille panel for hanging articles, as shown and described.

DESCRIPTION

FIG. 1 is a perspective view of a grille panel for hanging articles, showing my new design;

FIG. 2 is a reduced front elevational view thereof;

FIG. 3 is a reduced left side elevational view thereof, the side opposite being a mirror image;

FIG. 4 is a reduced top plan view thereof, the bottom being a mirror image;

FIG. 5 is a reduced rear elevational view thereof.

FIG.1

FIG.2

FIG.3

FIG.4
